United States Patent Office

Des. 209,426
Patented Nov. 28, 1967

209,426

CUP OR SIMILAR ARTICLE

Charles Lewis Metzler, Alpine, N.J., and Henry Albert Holzwarth, Bayside, N.Y., assignors to American Can Company, New York, N.Y., a corporation of New Jersey

Filed Dec. 12, 1966, Ser. No. 5,361

Term of patent 14 years

(Cl. D58—17)

Fig. 1.

Fig. 2.

FIG. 1 is a perspective view of a cup showing our new design; and

FIG. 2 is a fragmentary sectional view taken substantially along line 2—2 of FIG. 1.

We claim:

The ornamental design for a cup or similar article, substantially as shown.
